US0D1064421S

(12) **United States Design Patent** (10) **Patent No.:** **US D1,064,421 S**
(45) **Date of Patent:** **** Feb. 25, 2025**

(54) **HEARING PROTECTION EARMUFF**

(71) Applicant: **Ningbo Beilun Gillsen Electronic Co., Ltd**, Ningbo (CN)

(72) Inventor: **Hongyu Tao**, Ningbo (CN)

(73) Assignee: **Ningbo Beilun Gillsen Electronic Co., Ltd**, Ningbo (CN)

(**) Term: **15 Years**

(21) Appl. No.: **29/902,035**

(22) Filed: **Sep. 8, 2023**

(51) LOC (15) Cl. **29-02**

(52) U.S. Cl.

USPC **D29/112**

CLAIM

The ornamental design for a hearing protection earmuff, as shown and described.

DESCRIPTION

FIG. 1 is a front, top, and left side perspective view of a hearing protection earmuff, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the hearing protection earmuff, which form no part of the claimed design.

1 Claim, 7 Drawing Sheets
